UNITED STATES PATENT OFFICE

THOMAS C. KENNEDY, OF CHICAGO, ILLINOIS, ASSIGNOR TO FAIRBANKS, MORSE & COMPANY, OF CHICAGO, ILLINOIS, A CORPORATION OF ILLINOIS.

STORAGE APPARATUS.

No. 902,300.

Specification of Letters Patent.

Patented Oct. 27, 1908.

Application filed January 31, 1907. Serial No. 355,068.

To all whom it may concern:

Be it known that I, THOMAS C. KENNEDY, a citizen of the United States, residing at Chicago, Cook county, Illinois, have invented 5 certain new and useful Improvements in Storage Apparatus, of which the following is a specification.

My invention relates to storage apparatus or a system for the handling of coal, iron ore and the like and for depositing of the same into a storage space or pockets and the object of my invention is to provide novel and reliable apparatus of this character for the more advantageous and efficient handling and depositing of said materials.

In the drawing Figure 1 is a plan view of my improved storage system; Fig. 2 an end elevation thereof; Fig. 3 an end elevation of the movable structure or bridge; and Fig. 4 20 a detail view of the construction when pockets are employed either alone or in connection with the storage area.

My improved storage apparatus or system comprises essentially a bridge movable over 25 the storage area or pockets and provided with what I will term bridge tracks which are adapted to coöperate with stationary tracks at the sides of the storage area and coöperate also with a cable device for positively drawing the cars along the stationary tracks and also across the bridge in opposite directions, the construction and arrangement of my apparatus being such that the car eventually leaves the same end of the 30 bridge that it originally entered, regardless of the position of the bridge relative to the storage area.

Now referring to my apparatus in detail and referring to the present embodiment 40 thereof illustrated in the drawing, the same comprises a pair of stationary tracks 1, 1 extending longitudinally on opposite sides of a storage space or area which is herein indicated by the reference letter A. These 45 tracks may if desired be elevated as illustrated in Fig. 2 or may be at or near the ground in the event that the storage space is below the ground level or in case pockets are employed adjacent such stationary tracks, 50 but I will now proceed to describe my invention in connection with the structure herein disclosed.

Each pair of stationary tracks is continuous, the same being provided with loops 1' 55 at each end. With the innermost tracks of

each pair of the stationary tracks 1 bridge tracks 2 are adapted to coöperate. These bridge tracks are carried upon a movable structure or bridge 3 extending transversely of the storage area and running upon suitable tracks at either side of the storage area, the bridge structure in the present instance having depending portions terminating in rollers or wheels 4 adapted to travel on said tracks or rails. It will be understood that 60 this bridge structure is adapted to be moved longitudinally of the storage area in any suitable manner and by any suitable power. The bridge tracks 2 are curved at their ends so as to always connect with the innermost 70 tracks of the pairs of stationary tracks in whatever position the bridge may be in respect to the storage area and the stationary tracks.

It will be understood that the cars indicated by 5 may be loaded at any desired point but in the present instance I have shown the loading point in a more or less diagrammatic manner at 6 which is at one end of the right-hand stationary tracks 80 (Fig. 1) although such cars may be loaded at other points on the stationary tracks. These cars are adapted to be drawn by power and in a positive manner at all points in their course and to this end I employ a 85 continuous cable 7 which follows the stationary tracks (excepting immediately adjacent the bridge) and also the bridge tracks, the same running in opposite directions over the bridge. The cars are adapted to be 90 gripped to the cable in any suitable and well-known manner and remain gripped thereto at all times except of course at the point in the length of the cable where the same runs to the driving mechanism as in any cable 95 system.

Referring to Fig. 1 and assuming that a car has been loaded at the point 6, the same is caused to move along the innermost track 1 on the right-hand side of the storage area and will continue thereon until it reaches the curved end of the uppermost bridge track which switches it over upon the bridge where the car may be dumped of its material which will fall in the storage space below. 100 The car remains attached to its cable and runs off the bridge onto the innermost stationary track of the left-hand pair of tracks (Fig. 1) around the uppermost loop 1', along the outermost stationary track 1, 110

around the lowermost loop 1', then on to the innermost stationary track, across the bridge on the lowermost bridge track and thence back again to the point of loading by passing around the lowermost loop 1' of the right-hand pair of stationary tracks and the outermost stationary track on the right-hand side. It is thus apparent that the cars remain attached to their cable practically throughout the entire circuit of tracks in whatever position the bridge may be located and also that the cars traverse the bridge in opposite directions, leaving the bridge at the same end at which they enter.

15 It will be understood that pockets may be provided adjacent the stationary tracks into which the cars may be dumped of their materials, such pockets to be employed either alone or in connection with a storage area 20 or space, with both of which spaces my storage apparatus is designed to coöperate. These pockets may be arranged below the stationary tracks and within or in connection with the framework or structure 25 which supports said stationary tracks. Such construction and arrangement of pockets are shown in Fig. 4 in which the pockets are indicated at 9. When my apparatus or system is employed simply for the purpose 30 of filling the pockets the cars traverse the tracks, including the bridge tracks, in the manner hereinbefore described and the operation is the same with the exception that the cars are dumped while on the stationary 35 tracks instead of on the bridge tracks. Moreover, my construction obviates the necessity of a cross or connecting structure at one or both ends of the stationary tracks inasmuch as my bridge, in coöperation with 40 the bridge tracks, is capable of performing all functions of such end structures besides performing its main function of bringing the cars to the desired point for dumping purposes and for returning them to the loading 45 point.

I claim:

1. In a storage apparatus, the combination of a pair of parallel stationary tracks arranged on one side of the storage area and 50 connected by loops formed at their opposite ends and located at two adjacent corners of said storage area, a bridge movable longitudinally of said tracks, and a pair of parallel tracks on said bridge connecting with one 55 of the stationary tracks in all positions of the bridge and arranged to permit cars to traverse said bridge and to enter and leave at the same end thereof.

2. In a storage apparatus, the combination of two pairs of stationary tracks ar-

ranged on opposite sides of the storage area, a bridge movable longitudinally of said tracks, a pair of parallel tracks on said bridge connecting with one of the stationary tracks in all positions of the bridge and arranged to permit cars to traverse said bridge and to enter and leave at the same end thereof, and an endless cable along said stationary tracks and the bridge tracks arranged to draw cars therealong, the members of each 65 pair of stationary tracks being connected by end loops and such pairs of tracks being unconnected except through the medium of the bridge tracks.

3. In a storage apparatus, the combination of a pair of stationary parallel tracks connected by end loops, a bridge movable longitudinally of said tracks, and a pair of parallel tracks on said bridge both connecting by curved portions with one of the stationary tracks in all positions of the bridge and arranged to permit cars to traverse said bridge in opposite directions and to enter and leave at the same end thereof. 75

4. In a storage apparatus, the combination of two pairs of stationary parallel tracks arranged at opposite sides of a storage area or the like, a bridge movable longitudinally of said tracks, and a pair of tracks on said bridge both curved at their opposite 80 ends to connect with the innermost member of each pair of stationary tracks, the tracks of each pair of stationary tracks being connected by end loops and the two pairs of such tracks being connected by the bridge 85 tracks for the travel of cars in opposite directions across said bridge so that the cars enter and leave the bridge at the same end. 90

5. In a storage apparatus, the combination of two pairs of stationary parallel 100 tracks arranged at opposite sides of a storage area or the like, a bridge movable longitudinally of said tracks, a pair of tracks on said bridge both curved at their opposite ends to connect with the innermost member 105 of each pair of stationary tracks, the tracks of each pair of stationary tracks being connected by end loops and the two pairs of such tracks being connected by the bridge 110 tracks for the travel of cars in opposite directions across said bridge so that the cars enter and leave the bridge at the same end, and a cable along the pairs of stationary tracks and the bridge tracks to positively draw cars therealong. 115

THOMAS C. KENNEDY.
